UNITED STATES PATENT OFFICE.

GEORGE CLARENCE BROOKS, JR., OF CAMDEN, NEW JERSEY.

RADIO TUNING COIL.

Application filed April 11, 1925. Serial No. 22,354.

My invention relates to tuning coils especially designed for use with radio receiving apparatus.

The current losses in tuning coils are largely caused by defective insulation between the coil turns and the losses are increased if the insulating material becomes moist. These losses are detrimental to proper reception of broadcast matter. The coils in use are of two classes, covered wire coils, and bare wire coils. The chief objection to the covered wire coils is that the insulating covering absorbs moisture. The chief objection to the bare wire coils is that the coil turns, being necessarily spaced from each other, make a large and clumsy coil which is undesirable. Another objection common to both types of coils is that it is practically impossible to eliminate howls and other tube noises without sacrificing regeneration.

The objects of my invention are to provide a neat and compact tuning coil which will be practically free from current losses due to insulating material between its turns; which may be easily controlled to eliminate howls and other tube noises; which will have maximum regeneration at all times; which is sensitive and selective in tuning, and with which broadcast matter may be received with a great volume and clearness of tone.

These objects, and other advantageous ends which will be described hereinafter, I attain in the following manner, reference being had to the accompanying drawings in which

Figure 1 is a side elevation of a tuning coil made in accordance with my invention illustrating it attached to a panel,

Figure 2 is a diagram of the electrical connections between the tuning coil shown in Figure 1 and radio receiving apparatus,

Figure 3 a central vertical section through the coil shown in Figure 1,

Figure 4 a section on line 4—4 of Figure 3,

Figure 5 a section on line 5—5 of Figure 3, and

Figure 6 a bottom plan view of the coil shown in Figure 1.

Referring to the drawings, particularly Figure 2, the aerial circuit includes an aerial 1, a primary 2 and a ground 3; the grid circuit, a main secondary 4, a supplemental secondary 5, primary 2, and the filament 6 and grid 7 of an audion tube; and the aerial

circuit, a plate 8, an adjustable regeneration coil 9, a fixed regeneration coil 10, recorders 11, batteries 12 and filament 6.

The secondary coils 4 and 5, primary coil 2 and regeneration coils 9 and 10 are mounted on a frame 13 of insulating material. This frame is made up of an inner series of rods 14 and an outer series of rods 15 of insulating material connected and spaced from each other by insulating spacers 16 at one end and 17 at the other end. The spacers are preferably of ring shape and connected to the inner series of rods 14 by fitting the rods in holes 18 in the spacers. The outer series of rods 15 is connected to the spacers by securing the rods in slots 19 in the periphery of the spacers. This facilitates the securing of the outer series of rods 15 to the spacers after a coil has been wound around the inner series of rods 14.

Each of the rods 14 and 15 has grooves 20 therein for receiving and properly spacing the bare wire turns of the coils. The main secondary 4 is wound around the inner series of rods 14 with its turns within the grooves. Its end is then brought out between rods 15 and wound around them with the wire turns within their grooves to make up the supplemental secondary coil 5 and the primary 2. The aerial is connected to a terminal 22, which is connected to one end of the primary 2 at 23. The other end of the primary is connected with a terminal 24 adapted to be connected with the ground 3. The free end of the main secondary is connected with a terminal 25 adapted to be connected with grid 7. The fixed regeneration coil 10 is wound around the outer series of rods 15 with its turns within grooves 20 and has one end connected with a terminal 26 and the other end connected through a terminal 27 to the adjustable regeneration coil 9. Terminals 24 and 26, being mounted near each other on spacer 17, allow a by-pass condenser 28, which bridges recorders 11 and batteries 12 shown in Figure 2, to be directly connected to the terminals, as shown in Figures 4 and 6. This eliminates a separate condenser mounting and shortens the connecting wires of the condenser.

Adjustable regeneration coil 9 is wound to embrace the ends of a bar 29 having grooves 30 in which the turns of the coil are mounted. Bar 29 is suitably secured to a shaft 31, which is slidable and rotatable in a bearing 32 secured to a bracket 33 extend-

ing from spacer 16. Bearing 32 is preferably in the form of a bushing which may extend through a panel 34 and be secured thereto by a nut 36, and thus serve as a means for attaching the tuning coil to a panel.

By connecting the main secondary in series with the supplemental secondary and the primary, greater selectivity is obtained without having the losses inherent in tuning coils inductively coupled. By providing a fixed regeneration coil adjacent the primary so that it overlays one end of the secondary, and another adjustable regeneration coil near the other end of the secondary, howls and other tube noises may be eliminated and maximum regeneration obtained at all times. By mounting shaft 31 slidably and rotatably in the bearing, coil 9 may be shifted and rotated as shown in dot-and-dash lines in Figures 3 and 5 to the position in which best results are obtained and thus give a wide range of adjustment. By using bare wire and mounting it on a series of grooved spaced insulating rods, as above described, the insulating material between the coil turns is minimized and current losses decreased, and the size of the tuning coil is reduced.

In actual use I have found this tuning coil to be very sensitive for distant reception; to produce a greater volume and clearness of tone than known coils and to be easily controlled to eliminate howls and other tube noises without sacrificing the volume of tone.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a tuning coil a main secondary; a supplemental secondary in series with and overlaying the main secondary, and a primary comprising a portion of the supplemental secondary being spaced from and overlaying the main secondary.

2. In a tuning coil a main secondary; a supplemental secondary in series with and overlaying the main secondary; a primary comprising a portion of the supplemental secondary and overlaying the main secondary, and a regeneration coil adjacent the primary and overlaying the main secondary.

3. In a tuning coil a main secondary; a supplemental secondary in series with and overlaying the main secondary; a primary comprising a portion of the supplemental

secondary and overlaying the main secondary; a fixed regeneration coil at one end of the main secondary, and an adjustable regeneration coil in series with the fixed regeneration coil and disposed at the other end of the main secondary.

4. In a tuning coil a main secondary; a supplemental secondary in series with and overlaying the main secondary; a primary comprising a portion of the supplemental secondary and overlaying the main secondary; a fixed regeneration coil overlaying one end of the main secondary, and an adjustable regeneration coil in series with the fixed regeneration coil and disposed at the other end of the main secondary.

5. In a tuning coil a main secondary; a supplemental secondary in series with and overlaying the main secondary; a primary comprising a portion of the supplemental secondary and overlaying the main secondary; a fixed regeneration coil overlaying one end of the main secondary, and an adjustable regeneration coil in series with the fixed regeneration coil and disposed at the other end of the main secondary, the adjustable regeneration coil being normally disposed within the main secondary.

6. In a tuning coil a main secondary; a supplemental secondary in series with and overlaying the main secondary; a primary comprising a portion of the supplemental secondary and overlaying the main secondary; a fixed regeneration coil adjacent the primary and overlaying the main secondary, and an adjustable regeneration coil in series with the fixed regeneration coil and normally disposed within the main secondary.

7. A tuning coil including two series of insulating coil holding elements disposed one series within the other; spacers secured to the elements for keeping them apart; a main secondary wound on the inner series of coil holding elements; a supplemental secondary in series with the main secondary and wound on the outer series of elements, and a primary wound on the outer series of elements and connected in series with the supplemental secondary.

8. A tuning coil including two series of insulating coil holding elements disposed one series within the other; spacers secured to the elements for keeping them apart; a main secondary wound on the inner series of elements; a supplemental secondary in series with the main secondary and wound on the outer series of elements; a primary wound on the outer series of elements and connected in series with the supplemental secondary; a fixed regeneration coil wound on the outer series of elements, and an adjustable regeneration coil in series with the fixed regeneration coil and disposed at the end of the main secondary.

9. A tuning coil including two series of

insulating coil holding elements disposed one series within the other; spacers secured to the elements for keeping them apart; a main secondary wound on the inner series of 5 elements; a supplemental secondary in series with the main secondary and wound on the outer series of elements; a primary wound on the outer series of elements and connected in series with the supplemental secondary; 10 a fixed regeneration coil wound on the outer series of elements; a bracket mounted on one of the spacers; adjustable means mounted in the bracket, and a regeneration coil mounted on said means and connected in 15 series with the fixed regeneration coil.

10. A tuning coil including two series of insulating coil holding elements disposed one series within the other; spacers secured to the elements for keeping them apart; a main

secondary winding on the inner series of 20 elements; a supplemental secondary winding on the outer series of elements and in series with the main secondary winding; a primary winding on the outer series of elements and connected in series with the supplemental 25 secondary winding; a fixed regeneration winding on the outer series of elements; a bracket mounted on one of the spacers; adjustable means mounted in the bracket; a regeneration winding mounted on said means 20 and connected in series with the fixed regeneration winding, and terminals on the other spacer and electrically connected with the windings.

In testimony whereof I have signed my name to this specification.

GEORGE CLARENCE BROOKS, JR.
